DECIMAL POINT LOCATOR FOR SLIDE
RULES

Charles Christen, Hastings on Hudson, N. Y.

Application May 2, 1946, Serial No. 666,655

9 Claims. (Cl. 235—64.3)

1

This invention relates to a device for locating the decimal point in a number representing the multiplicand or quotient resulting from an arithmetical or mathematical calculation.

The principal object of the present invention is the provision of a simple device in combination with a conventional slide rule whereby the user following simple precautions may readily locate the decimal point between digits of an equation in a visual manner.

The nature of the invention and its distinguishing features and advantages will appear when the following specification is read in conjunction with the accompanying drawing, in which—

Fig. 1 is a side view of a conventional slide rule with the device of the present invention applied thereto, certain of the scales of the slide rule having been omitted, and the decimal point locator being shown in its first position.

Fig. 2 is a fragmentary side view of the slide rule showing the locator in its second position.

Fig. 3 is a view similar to Fig. 2, but showing the locator in its third position.

Fig. 4 is a side view of the cursor or indicator per se.

Fig. 5 is a side view of the digit counter bar per se.

Fig. 6 is a sectional view taken on the line 6—6 of Fig. 3.

Fig. 7 is an enlarged sectional view taken on the line 7—7 of Fig. 1.

Fig. 8 is a fragmentary side view showing a modification.

The device of the present invention is combined with a conventional slide rule comprising a stock 10, slide 11 and cursor or indicator 12. The stock 10 and slide 11 have the conventional scales which are incompletely shown yet sufficiently to give a simple example of the use of the device.

In accordance with the invention, the front transparent panel 13 of the indicator 12 has a decimal point 14 in line with the hairline 15. The panel 13 also has a multiplication sign 16 and a division sign 17 arranged side by side in spaced relation to each other. The indicator 12 is constructed to provide a guideway 18 parallel to the top edge of the stock 10. The panel 13 has a slot 19 therein and the back transparent panel 20 and top spacer have a slot 21 therein similar to the slot 19. Both slots open into the guideway 18. A digit tally bar 22 is slidable longitudinally in the guideway 18 disposed par-

allel to the top edge or longitudinal axis of the stock 10. The bar 22 is rectangular in cross-section to conform to the cross-sectional shape of the guideway. The bar has a series of holes 23 extending transversely therethrough to receive a manipulator consisting of a pin 24 having a knob 25. The holes 23 in line with the slots 19 and 21 are spaced equi-distantly a distance equal to the spacing of the signs 16 and 17. The length of the slots 19 and 21 approximates the distance between a pair of the holes 23 directly adjacent each other. The bar 22 also has a reference or tally mark 26 in the form of a short line. It occurs midway between the center pair of holes 23, as shown most clearly in Fig. 5. The stock 10 at the top edge has an extra single scale 27 consisting of ciphers or zeros 28 representing minus digits, and X's 29 representing plus digits. The zeros indicate numbers with values less than 1, such as .0012. These reference characters 28 and 29 are spaced equi-distantly with respect to each other and equal the spacing of the holes 23. It is also to be noted the distance between the decimal point 14 and the mark 26 is equal to the distance between any two holes 23 directly adjacent each other.

From the foregoing it will be understood a slide rule in combination with the above described device may be used to shift the relationship between the number of digits in a problem and the location of the decimal point as the indicator 12 is moved through its usual positions as is done in finding the answer to a certain problem. For example: 12×2 has three plus digits which are represented on the scale 27 thus: 0 X X X. The pin 24 is inserted into a selected hole 23 by virtue of the slots 19 and 21. The pin is brought into registry with the multiplication sign 16. The pin is thus disposed against the left end wall of the slots and the digit tally mark 26 is in alignment with the decimal point 14 and the hairline 15, and all three are brought into line with the first factor, namely, 12, in the problem aforesaid at the start, as shown in Fig. 1. The indicator 12 is then moved through its usual positions by grasping and laterally pushing on the knob 25. At the start of this movement, the bar 22 slides to the right one space before the indicator moves. This shifts the mark 26 one space followed by the movement of the indicator 12 and the bar 22 in unison, as indicated in Fig. 2. Now remembering simply that the problem involves three plus digits, the indicator 12 is brought into the required relation to the scale 27 in which the digit tally mark 26

spaces off three digit signs 29 counting the farthest to the left sign 29 and proceeding to the right. This brings the decimal point 14 after the second digit sign 29 thus: 0 X X X which indicates that the answer is twenty-four. If for example it is desired to solve the problem $12 \times 2 \times 3 \times 4$ as a continuation of the problem 12×2 , it is observed that the mark 26 has shifted one space to the right and that the hairline 15 is in line with the graduation (24) on the scale 27, as shown in Fig. 2. The procedure then is as follows: Place the left index of the slide in line with the graduation for 24 and without disturbing the position of the bar 22 or the hairline 15 remove the pin 24 from its present location and place it in the hole which is in registry with the multiplication sign 16. The indicator 12 is again moved through its usual positions by grasping and laterally pushing on the knob 25. At the start of this movement, the bar 22, along with the mark 26, again slides one space to the right and when the hairline 15 arrives at the third factor (3) the mark 26 has shifted two spaces to the right of the point where it started from, which was in line with the decimal point. The hairline 15 is now in line with the graduation for 72. The right index of the slide is now brought in line with the graduation for 72 and, as before, the pin 24 is removed and placed into registry with the multiplication sign 16. The indicator 12 is now moved to the fourth factor (4) by grasping and laterally pushing on the knob 25. Please note that this movement is the opposite of the other movements and since the multiplication sign and the pin 24 are on the left side of the slot, this movement to the left will not cause any further shifting of the bar 22 or the mark 26. Now remembering that the problem involves five plus digits, the indicator 12 is brought into the required relation to the scale 27 in which the mark 26 spaces off five digit signs 29 counting the farthest to the left sign 29 and proceeding to the right. This brings the decimal point 14 after the third digit sign 29 thus: 0 0 X X X X which indicates in a visual manner that the answer is 288.00.

In solving a problem in division, namely,

$$\begin{array}{r} 12 \times 2 \\ \hline 5 \end{array}$$

the procedure for 12×2 as above described is carried out. In such case the hairline 15 will have been brought in line with the graduation (24) and the pin 24 is brought into registry with the division sign 17. Since the next operation is one of division, there is no need for resetting the pin. The graduation for 5 on the slide 11 is brought in line with the graduation for 24 and the hairline 15 is brought to the right index by grasping the handle 25. The hairline 15 is in line with the answer, but the graduations shown that it could be .48, 4.8, 48, 480 etc. The digit count for this example is +3 for the numerator and -1 for the denominator. This gives a sum of +2. When the mark 26 is used to space off +2 digits on the scale 27, the decimal point appears thus: 0 0 0 X X X X which denotes the answer to be 4.8.

It will be appreciated that by providing the extra scale 27 it is possible to properly locate the decimal point visually wherein the user is enabled to count off the digits consecutively in a simple manner. This means that the decimal point in even the most difficult problem can be located without making calculations on paper.

By providing a slot, such as the slot 19 in relation to the $\times$ and $\div$ signs, it is possible to use the pin 24 below one or the other of these signs according to a given problem without remembering complicated rules necessary in the use of an ordinary slide rule.

It is to be understood that in lieu of holes 23 extending through the bar, depressions may be used in which case only one slot is required. By 10 providing the holes 23 and the slots 21 at the back the device is useful with the scales on the back of the rule.

Also as shown in Fig. 8 in lieu of the holes 23, the bar 22 may have teeth 30 which coact with 15 a notched rotor 31 carried by the indicator 12 to slide the bar one space to the left or right according to whether the problem is one of multiplication or division. The rotor 31 has arrows 32 and 33, respectively, to indicate the multiplication or division setting of the bar 22. In other respects the device is similar to that shown in Figs. 1 to 7 and similar reference numerals are applied to corresponding features. The rotor 31 functions as a detent in coaction with any two 25 of the teeth 30 because it allows the bar 22 to move one space and then prevents further movement with respect to the indicator 12. The detent 31 is turned to the right for a problem in multiplication. The arrow 32 will point to the proper sign 16. Then by pushing on the left end 30 of the bar 22, the bar will slide one space and be stopped with respect to the indicator 13. On reference to Fig. 8 it will be apparent that as the bar 22 is slid to the right, the tooth 30 in 35 line with the mark 26 will cam the detent 31 so as to turn it to the left causing the third tooth 30 to the left of the mark 26 to encounter the detent 31, and so prevent further movement of the bar 22 to the right. In solving the 40 problem $12 \times 2 \times 3 \times 4$ with the modification shown in Fig. 8, the procedure heretofore set forth in connection with the pin 24, is followed, the detent 31 is set in the position shown in Fig. 8 for multiplication. The detent 31 is 45 always reset to the multiplication sign after each one space shift of the bar 22 to the right.

For a problem in division the detent 31 is turned to the left bringing the arrow 33 in the proper indicating position with respect to the sign 17. This enables the bar 22 to slide one 50 space to the left by pushing on the right end of the bar. In this event the detent 31 will have turned to the right. The detent is reset, as the case may be, and according to the problem to be solved. After the answer to the problem has been found, the indicator 13 together with the bar 22 in its adjusted position are slid along the stock into juxtaposition to the scale 28 to locate the decimal point according to the number of 55 digits in the answer.

I claim:

1. The combination with a slide rule having a 60 slidable indicator with a hairline and a decimal point on one face thereof, of a minus and plus digit scale on said rule, and a decimal point locator including a digit tally bar with an indicator mark thereon longitudinally adjustable on said indicator, said bar being adjusted with respect to said indicator to displace said mark relative to the decimal point, and said indicator with 65 said bar in the adjusted position being movable as a unit along the rule into position adjacent said scale, thereby showing the decimal point value of a result on the scale.

70 2. The combination as set forth in claim 1,

wherein said bar is longitudinally adjustable on said indicator by sliding said bar with respect to the indicator.

3. The combination as set forth in claim 1, wherein said indicator has a slot therein, and said bar has a series of equi-distantly spaced holes therein in line with said slot, and a pin engageable in any one of said holes through said slot, for causing adjustment of the bar with respect to the indicator and the movement of the bar and indicator in unison for the stated purpose.

4. The combination with a slide rule having a stock and an indicator having a hairline slideable along the stock, of a digit tally bar slideable longitudinally with and with respect to said indicator, said indicator having $\times$ and $\div$ signs thereon, side by side in spaced relation and a decimal point in line with the hairline, said bar having a digit tally mark thereon which is displaced relative to the decimal point upon adjustment of said bar with respect to the indicator, and a minus and plus scale on said stock, said indicator with the bar in the adjusted position being movable in unison along said stock, thereby showing the decimal point value of a result on said scale.

5. The combination as set forth in claim 4, wherein said indicator has a slot therein adjacent said $\times$ and $\div$ signs, said bar has a series of holes therein spaced equi-distantly, and a manipulator insertable in any one of said holes while extending through said slot to move the bar and indicator as stated.

6. The combination with a slide rule having a slideable indicator having a hairline and a decimal point in alignment with each other and multiplication and division signs spaced apart, of a digit tally bar slideable longitudinally with and with respect to said indicator, said bar having a digit tally mark thereon for alignment with said hairline, said bar having a series of teeth, a notched rotor on said indicator which coacts with said teeth to adjust the bar to the right or left to displace said mark relative to the decimal point, and to cause said indicator and bar in adjusted position to move in unison upon the manipulation of said bar, said rotor having arrows or the like thereon which point to said signs respectively to indicate the multiplication or division setting of the bar, and a minus and plus digit scale on the stock, said indicator and bar being movable in unison along said rule into

position adjacent said scale showing the decimal point value of a result on said scale.

7. The combination with a slide rule having a slideable indicator with a hairline and a decimal point thereon, of a minus and plus digit scale on said rule along one longitudinal edge thereof, said indicator having a guideway therein paralleling said edge, a digit tally bar having a digit tally mark thereon slideably adjustable in said guideway with respect to the indicator to displace said mark relative to the decimal point, and means to engage said bar and said indicator to cause the movement of said bar together with the indicator along the rule into juxtaposition to said scale to show the decimal point value of a result on said scale.

8. The combination as set forth in claim 7, wherein said last means consists of a manipulator adapted to extend through aligned slots in said indicator and any one of a series of holes in said bar.

9. The combination with a slide rule having a stock and an indicator having a hairline slideable along the stock, of a digit tally bar adjustable with respect to said indicator and also movable therewith along said stock, said indicator having $\times$ and $\div$ signs thereon side by side in spaced relation and a decimal point in line with said hairline, said bar having a digit tally mark between said signs for alignment with said hairline, said indicator having a slot therein and said bar having a series of holes therein spaced according to the spacing of said signs whereby a suitable manipulator may be engaged with said bar to adjust the bar with respect to the indicator and to move bar and indicator in unison, along said stock, and a minus and plus digit scale on said stock, said bar when adjusted with respect to the indicator displacing said mark relative to the decimal point, and said indicator and the bar when moved in unison along said stock into juxtaposition to said scale showing the decimal point value of a result on said scale.
